UNITED STATES PATENT OFFICE.

HENRY M. BROOKFIELD AND SIGWARD OLSEN, OF NEW YORK, N. Y., ASSIGNEES TO
THE BROOKFIELD GLASS COMPANY, OF NEW YORK, N. Y., A CORPORATION OF NEW
JERSEY.

MOLD.

1,144,527.

Specification of Letters Patent. Patented June 29, 1915.

Original application filed July 24, 1912, Serial No. 711,234. Divided and this application filed October 1, 1912. Serial No. 792,746.

To all whom it may concern:

Be it known that we, HENRY M. BROOKFIELD and SIGWARD OLSEN, citizens of the United States, residing at New York city, 5 State of New York, have invented certain new and useful Improvements in Molds, of which the following is a clear, full, and exact description.

This case is a division of a copending application, Serial No. 711,234, filed July 24, 1912.

The present invention relates particularly to molds in which plastic articles may be formed.

15 A principal object of the invention is to produce a mold from which the molded article can be readily ejected.

A further object of the invention is to insure reliability in the delivery of the article from the mold.

A general object of the invention is to produce a mold of very simple construction having advantageous and novel features.

The invention consists in the general combination of parts and simplicity of details to be hereinafter described, all of which contribute to produce an efficient mold.

30 A preferred embodiment of our invention will be particularly described in the following specification while the broad scope of our invention will be pointed out in the appended claims.

In the drawings, Figure 1 is a front elevation of a press with which our invention 35 may be employed; Fig. 2 is a vertical section through the lower portion of the press, illustrating the manner in which the article is formed in the mold and also illustrating the manner in which the finished article can 40 be ejected from the mold; Fig. 3 is a plan showing one of the molds in an open position, and Fig. 4 is a horizontal section through the lower part of the press.

45 Referring more particularly to the parts, 12 indicates the frame of the machine which may comprise a base plate 13, upon which a table 14 is supported. The said table 14 is preferably circular and the middle portion thereof is formed into a turn table 15, which 50 may support a worm wheel 16, which may be rotated continuously by means of a worm 17 carried by shaft 18 and driven through gearing 19 from a main shaft 20, said gearing being driven directly through bevel

gears 21. At the side of the machine and 55 supported on pulleys 22 there is preferably provided a delivery belt 23, which may be driven by a chain 24 from gearing 25 driven from a shaft 26, which latter shaft forms a part of the gearing 19. Rigidly secured on 60 the worm wheel 16 we provide a mold carrier 27, which is preferably of circular form and is provided with a plurality of molds 28 which may be equi-distant circumferentially upon the carrier. A preferred form 65 of one of these molds is illustrated in Figs. 2 and 3. Each mold preferably comprises two separable side parts 29 which are pivotally connected at 30 and adapted to swing apart laterally. Each mold preferably comprises also a base 31, the outer portion of 70 which forms a chamber 32 to receive the bottom part 33 of the mold. While the side parts 29 of the molds are adapted to swing away from each other in a horizontal plane, 75 the bottom part or cup 33 is adapted to swing outwardly, preferably in a vertical plane, for which purpose it may be provided with an arm 34 attached on a horizontal pivot 35, said arm carrying a roller 36 at 80 its outward extremity. Each mold is preferably provided with a latch or lock 37 in the form of a spring pressed trigger 38, having a hook 39 adapted to engage with a hook plate 40 on the opposite member, to 85 hold the side parts of the mold together, and directly over the bottom part 33, so that when the parts are together they form a complete mold to shape the exterior of the insulator or other article. The pivot pin 30 of the side parts has its lower end secured in 90 the carrier 27 and may have its upper end secured in a bracket 41, as shown in Fig. 2.

The bottom part 33 of each mold normally rests on a central adjusting screw 33^a held in plate 33^b.

After the mold is open as indicated in Fig. 3, the molded article can be ejected or delivered by automatic means co-operating with the lever 34, and to be described hereinafter.

The machine preferably is formed with a central tubular post 42 which houses the upper part of the main shaft 20, and this post supports rotatably an upper frame 105 plate 43. Between the frame plate 43 and the carrier 27 are provided a plurality of cross-head guides 44, between which verti-

- cally slideable cross-heads 45 are provided, and said cross-heads may be counterweighted by weights 47 supported on cords 48 passing over elevated pulleys 49 supported on the frame plate. The underside of each cross-head 45 is preferably provided with a follower 50, each of said followers comprising a plug 51, preferably of conical form, which is attached on the underside thereof.
- 5 10 Centrally disposed in each plug 51 there is a plunger 52 which passes down into the interior of the mold when the plug closes the mold so as to form a threaded interior in the molded article, if the article is an insulator such as indicated by 53 at the right of Fig. 2. In the operation of the machine after the insulator is formed, the plunger is withdrawn during a rotary movement which withdraws its threaded end 15 from the interior of the insulator without injuring the molded thread, and thereafter the follower rises and the plug also withdraws from the mold. The cross-heads carry rollers 54 which roll on the upper side 20 of the fixed cam 55 and this cam permits the cross-heads to descend at the proper times so that the followers may close their molds, as described above, but which will permit a limited upward movement.
- 25 30 In order to permit a cam 61 to open each mold at the proper moment, each mold is unlocked, and this may be accomplished as indicated in Fig. 4 by means of a pin 56 which projects upwardly from the table 14 in such a way as to strike the tails of the spring latches or locks 38. As soon as a mold is unlatched, it is pulled open automatically into the position shown in Fig. 3. This may be accomplished in any suitable 35 40 manner, such as by means of a cross-head 57, to which links 58 are attached, the outer ends of said links being attached through spring connections 59 with lugs 60 on the sides of the side parts 29 of the mold. Each 45 cross-head is pulled inwardly at the proper moment by means of the fixed cam 61 with which the inner end of each cross-head 51 is connected.
- 50 55 In order to deliver the finished article automatically from the mold, the cam roller 37 on the lever 34 of the bottom part of the mold engages with a cam or cam rail 92, as indicated in Fig. 2, and this swings the bottom part 32 of the mold into an elevated position over the belt 23 and near a guide 62 which guides the molded article down onto the belt when it falls out. The ends of the cam rail 92 may be supported on suitable posts 63, and in order to accomplish the 60 65 return movement of the lever 34, we may provide a spring frame 64 shown in Figs. 1 and 2.
- To insure that the molded insulator 65 held as indicated in Fig. 2 will become detached from the elevated bottom part 32,
- we prefer to provide an engaging member for dislodging it. This engaging member may have the form of a yoke 66, the end of which projects into the path of the insulator. This yoke is preferably formed on a lever 70 pivotally supported at 67 on one of the posts 63, and provided with a cam arm 68. This cam arm is adapted to be actuated in succession to dislodge the insulators, by pins 69 which may project radially from the 75 guides 44. The yoke 66 may be counterweighted by a weight 70, which normally holds the yoke elevated.
- In Fig. 1 the guide 62 is omitted to prevent it from hiding other parts of the mechanism.
- 80 After the molded article 65 is delivered, the bottom part 33 of the mold falls back by gravity into its normal position, and soon after this occurs the cam 61 forces out the 85 cross-head of this mold and the spring latch or lock 38 snaps over the hook plate 40 so as to hold the mold closed preparatory to receiving the next measured amount of stock.
- 90 The general mode of operation of the machine will be briefly reviewed. A measured or predetermined amount of stock, such as molten glass, is placed in one of the molds at the proper point on the machine, and as 95 the carrier rotates, the cam 55 permits the cross-head 45, corresponding to the filled mold, to descend. It will be understood that the cross-heads more than counterbalance the weight of the counterweights 47 100 and hence the cross-heads tend to descend. As the cross-head 45 descends, the plug 51 of the follower 50 closes the upper side of the mold. After the plunger has been withdrawn the mold is unlatched by the releasing pin 56 which engages the spring latch or lock 38 of the mold. The side parts 29 of the mold are then pulled apart by the opening cam 61, and as the rotation of the mold-carrier continues, the bottom part 33 105 of the mold swings upwardly and substantially radially away from the axis of the mold and away from the axis of the machine through the action of the cam rail 92 so as to overturn and eject or deliver the 110 molded article 65, which may be dislodged by the disengaging member or yoke 66 and delivered in an inverted position on the belt 23.
- 115 Although we have described the mold as 120 employed on an automatic press, it is understood that we are not limited in the use of the invention to presses but it may be applied to molds of any kind or for any purpose and operating upon any plastic substance or other substance capable of being molded.
- 125 It is understood that the embodiment of the invention described above is only one of the many embodiments the invention may 130

PRINT AVAILABLE COPY

take, and we therefore do not wish to be limited in the practice of the invention nor in our claims to the form or embodiment described.

5. What we claim as new is:—

1. A mold comprising a plurality of movable and separable parts arranged to receive a plastic substance and form an article therefrom when closed together, a part of 10 said mold being constructed and arranged to embrace the sides of the molded article and to support the article while said part carries said article from its position in the mold into overturned position, and a pivot 15 for said part about which it may swing for the purposes aforesaid.

2. A mold comprising separable side members and a bottom having portions adapted to engage the side of the molded 20 article in order that said bottom may carry the article from its position in the mold into overturned position, a pivot for said bottom, and means for effecting the movement of the bottom for the purposes aforesaid.

25 3. A mold having separable sides and a cup-shaped bottom, said bottom being adapted to embrace a substantial portion of the article molded, and a pivot for the bottom outside the mold about which the 30 bottom may swing bodily, when said sides are separated, from its position in the mold into a position to discharge the molded article with the bottom side uppermost.

4. A mold comprising separable side 35 members and a bottom having portions adapted to engage the side of the molded article in order that said bottom may carry the article from its position in the mold into overturned position, a pivot for said bottom 40 outside said mold about which the bottom may swing bodily for the purposes aforesaid, and means for swinging said bottom.

5. A mold comprising separable side members and a bottom having portions 45 adapted to engage the side of the molded article in order that said bottom may carry the article from its position in the mold into overturned position, a pivot for said bottom, and means co-operating with said bottom for 50 receiving and insuring the delivery in inverted position at a point remote from said mold of the molded article discharged by said bottom.

6. A mold comprising separable side 55 members and a bottom adapted to receive a plastic substance and form an article therefrom, said bottom having a rounded cup-shaped cavity adapted to embrace a sub-

stantial portion of the side of the article to be molded whereby it may be swung to deliver said article in inverted position, and being pivoted outside said mold for this purpose, means for swinging said bottom, and a guide for receiving said article and insuring its delivery to a receiving surface 60 65 in inverted position.

7. A mold comprising separable side members and a bottom having portions adapted to engage the side of the molded article in order that said bottom may carry 70 the article from its position in the mold into overturned position, a pivot for said bottom, means for effecting the movement of the bottom for the purposes aforesaid, and means for dislodging the article from said 75 bottom when said bottom has brought the article into overturned position.

8. In a press for molding articles, in combination, a movable carrier having a plurality of molds mounted thereon, each mold 80 comprising laterally swinging side parts and an upwardly swinging bottom part, all arranged to form an article when closed, means for automatically opening and closing said parts as said carrier moves, said 85 bottom part acting to deliver the formed article in inverted position at the delivery point at one side of said mold when said parts are opened, and an engaging member mounted adjacent said carrier and actuated 90 thereby to prevent the molded articles from being carried beyond the delivery point.

9. In a glass pressing machine in combination, a rotatable carrier having a plurality of molds mounted thereon, each mold 95 comprising horizontally swinging side parts and a vertically swinging bottom part, all arranged to form an article when closed, means for automatically opening and closing said parts during the rotation of the 100 machine, said bottom part acting to deliver said formed article in inverted position at one side of said mold when said parts are opened, and an engaging member mounted adjacent said rotary carrier and actuated 105 thereby to swing into the path of said glass articles and prevent the same from being carried there-beyond with the traveling molds.

Signed at New York, New York this 27th 110 day of September 1913.

HENRY M. BROOKFIELD.
SIGWARD OLSEN.

F. JACKSON.

It is hereby certified that in Letters Patent No. 1,144,527, granted June 29, 1915, upon the application of Henry M. Brookfield and Sigward Olsen, of New York, N. Y., for an improvement in "Molds," errors appear in the printed specification requiring correction as follows: Page 2, line 47, for the reference-numeral "51" read 57; page 3, line 9, for the word "closel" read *closed*; and that the said Letters Patent should be read with these corrections therein that the same may conform to the record of the case in the Patent Office.

Signed and sealed this 27th day of July, A. D., 1915.

[SEAL.]

R. F. WHITEHEAD,

Acting Commissioner of Patents.
